DESIGN FOR A STRAW AND NAPKIN HOLDER

Peter Beghetti, San Francisco, Calif.

Application May 26, 1947, Serial No. 139,283

Term of patent 3½ years

(Cl. D44—24)

To all whom it may concern:

Be it known that I, Peter Beghetti, a citizen of the United States, residing at San Francisco, State of California, have invented a new, original, and ornamental Design for Straw and Napkin Holder, of which the following is a specification, reference being had to the accompanying drawing, forming a part hereof.

Fig. 1 is a perspective view of a straw and napkin holder, showing my new design.

Fig. 2 is a top plan view.

Fig. 3 is a reduced size elevational view as seen from one napkin holding side.

Fig. 4 is a reduced size elevational view as seen from the opposite napkin holding side.

I claim:

The ornamental design for a straw and napkin holder, as shown.

PETER BEGHETTI.
